[57] **CLAIM**

The ornamental design for a computer peripherals housing, as shown and described.

DESCRIPTION

FIG. 1 is front, right side top perspective view of our computer peripherals housing;

FIG. 2 is a front elevational view thereof;

FIG. 3 is a top plan view thereof;

FIG. 4 is a side elevational view thereof, the opposite side being identical thereto;

FIG. 5 is a rear elevational view thereof;

FIG. 6 is a bottom plan view thereof;

FIG. 7 is a front elevational view of a second embodiment thereof the remaining views being identical to those in FIGS.

1-6 and the broken lines are shown for illustrative purposes only and form no part of the claimed design;

FIG. 8 is a bottom plan view of a third embodiment thereof;

FIG. 9 is a front elevational view thereof; and,

FIG. 10 is a side elevational view thereof the opposite side being identical thereto and the undisclosed top plan and rear elevational views are identical to those shown in the first embodiment.
